POWER SUPPLY METERING PANEL

Edward Brenner, Commock, Marvin Price, South Ozone Park, and Benjamin Shmurak, Lynbrook, N.Y., assignors to Lambda Electronics Corporation, Huntington, N.Y.

Filed Nov. 3, 1970, Ser. No. 25,797

Term of patent 14 years

Int. Cl. D14—99

U.S. Cl. D26—1

The figure is a perspective view of a power supply metering panel embodying our new design. Broken lines are shown for illustrative purposes only and do not form part of the claim.

This is a continuation-in-part of design application Ser. No. 18,702, filed Aug. 15, 1969 and now abandoned.

We claim:

The ornamental design for a power supply metering panel, as shown and described.
